UNITED STATES PATENT OFFICE.

GARDNER L. HOLT, OF SPRINGFIELD, MASSACHUSETTS.

IMPROVEMENT IN MODE OF ATTACHING ERASERS TO PENCILS.

Specification forming part of Letters Patent No. 86,753, dated February 9, 1869.

To all whom it may concern:

Be it known that I, GARDNER L. HOLT, of Springfield, in the county of Hampden and Commonwealth of Massachusetts, have invented a new and Improved Erasing Attachment for Lead-Pencils; and I do hereby declare that the following is a full, clear, and exact description thereof, reference being had to the annexed drawings, making a part of this specification, and to the letters of reference marked thereon, in which—

Figure 1 is an elevation of an ordinary lead-pencil having my improved attachment applied thereto. Fig. 2 is an axial sectional view of said attachment. Fig. 3 is also an axial sectional view of the same, the rubber being shown as partially crowded out to compensate for wear by turning in the pencil. Fig. 4 shows a modified form of said attachment, the ferrule being divided by a longitudinal cut.

My invention consists of a small cylindrical piece of vulcanized caoutchouc, or other similar elastic material, which can be used for erasing the marks made by lead-pencils and cleaning the surface of paper, which erasing substance is inserted within a ferrule of thin sheet metal, so that enough of the rubber projects at one end of the ferrule to serve as an eraser, while the opposite end of the rubber extends down nearly to the other end of the ferrule. The rubber is made of such a diameter as to fill the ferrule completely and be held within the same by its pressure against the sides.

A shallow screw-thread is cut upon the inside of one end of the ferrule, extending a short distance into the ferrule, and, if applied to a wood pencil, the ferrule can be turned so that the screw-thread will engage with the wood of the pencil and cut a shallow corresponding male screw-thread upon the wood, and thus draw the pencil into the ferrule as far as necessary. By this screw-thread in the ferrule the latter is not only held firmly upon the pencil, but, by turning the pencil within the ferrule, I am also enabled to advance the pencil into the ferrule, and thus push out the rubber as fast as its projecting end is worn away by use. Nearly the whole of the rubber can thus be utilized, while it is kept clean and entire until thrust out at the end of the ferrule.

As the diameters of the wood pencils in

market are variable, I construct a modified form of the attachment, in which the ferrule, otherwise formed as before described, is divided by a longitudinal cut on one side, as shown in Fig. 4, so as to clasp tightly the end of the pencil, whether it is larger or smaller, without trimming the wood so as to enter the ferrule.

The construction of my invention, as shown in Fig. 1, is as follows: The ferrule A is made of a convenient length—about three-fourths of an inch—and of an inside diameter to correspond with the size of pencils to which it is to be applied, and the interior is smoothly finished and has a female screw-thread, a, cut at one end, the thread of which projects slightly into the ferrule, so as to engage with the wood of the pencil.

In forming the ferrule, the threaded end can be made slightly thicker inside, so as to allow the screw-thread to project beyond the smooth inner face of the ferrule to the depth of the thread, or thereabout.

A small cylindrical piece, B, of erasing material, vulcanized caoutchouc, or like erasive substance, is formed, of such a diameter as to press snugly into the ferrule, and long enough at the opposite end for the pencil to enter the ferrule sufficiently to attach the latter securely to the former by the screw-thread.

In practice, the erasing-pieces can be readily cut in lengths from a cord of vulcanized rubber of the proper diameter, and thus made perfectly uniform, while the ferrules can be struck up in the same manner as cartridge-shells are now made, thus making the whole attachment very cheaply and uniformly.

The ferrules may be made of gutta-percha, or hard rubber, or other like material.

In operation, it will be seen that as the rubber is worn away at the erasing end the pencil can be screwed further into the ferrule, so as to push the rubber out and maintain the proper projection for erasing, as is shown in Fig. 3, when the pencil has been somewhat advanced.

In some cases a male screw-thread may be advantageously cut upon the pencil to engage with the female screw-thread in the ferrule.

Instead of holding the rubber within the ferrule by its pressure against the sides, the rubber may be rigidly cemented to the end of the

pencil and then pushed forward, as before described; but I prefer the method of construction before described as more simple and effectual.

I do not claim, broadly, an erasing-tip so arranged as to slide out of a pencil-case, as such a device has been in use; but I believe that an erasing attachment composed of a piece of vulcanized rubber, or like material, inclosed within a ferrule which has a female screw-thread cut upon it, and is arranged so as to be applied to a wood pencil, as set forth, to hold the ferrule upon the pencil and to push the rubber out of the ferrule, to compensate for wear, to be new.

Having described my invention, what I claim as new therein, and desire to secure by Letters Patent, is—

① An erasing attachment for lead-pencils composed of the ferrule A, having the screw-thread *a* formed therein and the erasing material B applied thereto, and the whole constructed and arranged substantially as and for the purpose set forth.

② The combination of the ferrule A', divided longitudinally, and having a female screw-thread cut therein, and the erasing material B applied to such ferrule, substantially as and for the purpose set forth.

In witness whereof I have hereunto set my hand this 22d day of July, A. D. 1868.

G. L. HOLT.
